UNITED STATES PATENT OFFICE.

JAMES W. LAWHEAD, OF WILMINGTON, OHIO.

APPARATUS FOR FEEDING BATTER TO A BAKING-MACHINE.

1,171,447.

Specification of Letters Patent. Patented Feb. 15, 1916.

Application filed March 4, 1912. Serial No. 681,429.

To all whom it may concern:

Be it known that I, JAMES W. LAWHEAD, a citizen of the United States, residing at Wilmington, in the county of Clinton and State of Ohio, have invented certain new and useful Improvements in Apparatus for Feeding Batter to a Baking-Machine, of which the following is a specification.

My invention relates to apparatus for feeding batter to a baking machine and is particularly designed to provide a simple and compact structure of apparatus calculated to segregate a definite proportion of the batter from bulk and to transfer said portion of batter to a point of delivery and to finally deposit such batter at the said point of delivery.

My invention aims to provide an apparatus which is in connection with a source of batter supply and which is positively effective to select the desired proportion of the batter and by positive operation throughout to transfer and deliver the same as stated. The positive operation of selecting the determinate portion of batter is desirably effected by the utilization of a particular structure of pump and by the creation therein of a partial vacuum tending to positively draw the definite portion of the batter into the pump. The subsequent operations preferably consist in pocketing the said selected portion of batter and without compression of the same, carrying it to a point of deposit and then by means of compression of the said selected portion of the batter, positively ejecting the same through a delivery port provided therefor and in proper relation to a passing baking plate.

My invention is peculiarly adaptable to a chain type of ice cream cone baking machine, although it is not limited in its various phases to such use.

The preferred embodiment of my invention is shown in the accompanying drawings and in this form of depositing apparatus, there are utilized two pistons working within a cylinder and desirably effective by certain distinct steps of operation. These steps are illustrated by Figures 2, 3 and 4 and they comprise the drawing in of the batter into the cylinder by relative movement of the pistons from the position shown in Fig. 2 to that shown in Fig. 3; the movement of the pistons simultaneously and while in stationary relation to each other to the point of deposit; and the bringing together of such pistons above the delivery opening of

the cylinder to effect the deposit. These steps are briefly outlined at the beginning of this specification to assist in a complete understanding of the mechanism to be subsequently described.

In the drawings, similar characters of reference designate corresponding parts and, therein:

Fig. 1 is a side elevation of a baking machine of the general type to which my invention is applied, Fig. 2 is a detail showing the position of the pistons of my apparatus just prior to the drawing in of the batter from its source of supply to the cylinder, Fig. 3 is a similar detail view of my device applied to a chain type of baking machine and showing the pistons in their second relative position, at which time they have positively drawn in the desired quantity of batter, Fig. 4 is a detail view showing the position of the pistons, which has been assumed in the positive delivery of the selected portion of batter and which relative position is maintained during the return of the pistons to the position shown in Fig. 2, Fig. 5 is a plan view of the structure shown in Fig. 3, Fig. 6 is an end elevation of the structure shown in Fig. 3, and, Figs. 7 and 8 are details of the latch structure which is desirably utilized by me to automatically connect and disconnect the two pistons.

In the drawings, there is shown a baking machine of the chain type, comprising a base 1, endless complementally traveling chains 2 and 3 and controlling gears and sprockets 4. The endless chains 2 and 3 are desirably formed from baking plates 5 and 6 which may be heated in any desired manner and which are shown as being linked together and provided with laterally extending rollers or pins 7 and 8 to which conform the driving sprockets mentioned. The chain type of machine to which my invention is preferably applied, comprises a lower chain element whose receiving end extends beyond the end of the upper chain and this extended portion provides a ready receiving surface for batter to be deposited on the baking plates. The power may be transmitted to the machine by a pulley as at 9 or in any other desired manner.

The base element 1 carries at the extended end of the lower chain a U-shaped saddle element 10 and vertically extending arms 11 which are individually disposed upon either side of the base element. These arms 11 are preferably connected to the saddle element

10 by spanning braces 12. The saddle element 10 serves to support a cylinder 13 having an inlet port 14 and an outlet port 15, this outlet port 15 being desirably transversely elongated and being in the form of a tapered base 16 whereby batter ejected through the same, will have a confined discharge area. Extending from one end of the cylinder, I desirably provide a multi-face 10 cam element 17 having faces 18 and 19. This element 17 may be integrally carried by the cylinder and such cylinder is likewise provided with a feed pipe 20 threaded into an enlargement of the port 14 and leading 15 from a batter containing can 21.

The multiple piston element utilized in my invention, comprises a piston 22 adjustably threaded upon its stem 23, which is carried by a yoke element 24, being desirably immovable thereon. The yoke element 20 24 has legs 25 and 26 and spanning pieces 27 and 28. The spanning piece 28 is bored for the sliding reception of the stem 30 of a complementary piston 29 and this stem 30 is 25 preferably adjustably threaded into the piston 29. Carried at or near the outermost end of the stem 30 is a transverse pin 31 which works in a slot 32 of a pivoted latch 33 operating in conjunction with the trans- 30 verse bar 28 and pivotally carried at its outer end by the depending bar 34 which it straddles. The latch 33 has a hook element 35 which is capable of assuming either the 35 position shown in Fig. 2 or the position shown in Fig. 3. It is caused to move upwardly into one or the other of these positions by means of the dogs 36 and 37 which are individually yieldable in one direction, but positively coöperate respectively with 40 surfaces 19 and 18 in their movements in opposite directions. At this point, it may be well to explain that the initial position of the positive elements is shown in Fig. 2 and that positive movement of the latch element 45 toward the left under control of mechanism to be hereinafter described, causes the latch dog 37 to coöperate with the surface 18 and to thereby lift the latch element 35 so as to release it from the transverse bar 28. Then, 50 continued movement of the latch element operates through means of the slot 32 and pin 31 to draw the piston 29 and stem 30 away from close relation to the piston 22 which is maintained against further movement 55 by the contact of the transverse bar element 27 with the end of the cylinder. Inasmuch as this piston 22 is maintained against further movement toward the left by the contact of the transverse bar 24 with the 60 end of the cylinder, further movement toward the left of the piston 29, which necessarily results after the release of the latch 33 from the transverse bar 28, produces a partial vacuum and tends to draw the batter 65 into the cylinder through the pipe 20 and

inlet port 14. When a sufficient quantity of the batter is drawn into the cylinder, the piston 29 is caused to cease its movement by operation of the mechanism yet to be described and the latch element 33 is caused to move toward the right. At the initial moment of the movement of this latch element toward the right, the said latch element is in the position shown in Fig. 3 and therefore causes the yoke 24 to move toward the right likewise. Continued movement in this direction, carries both pistons toward the right in relatively unchanging positions until the dog 36 moves into contact with the cam surface 19, which in time causes the latch element to lift. This lifting takes place when the selected portion of the batter is above or substantially above the outlet port 15 of the cylinder and necessarily results in a movement of the piston 29 toward the right while the piston 22 is precluded from further movement toward the right by contact of the transverse bar 28 with the left-hand end of the cylinder. This, of course, results in a bringing of the pistons together and in a compression of the batter therebetween. This compression of the batter positively forces it through the outlet port 15 and on to the baking plate therebeneath. The transversely elongated form of the delivery port is effective to compensate for the traveling movement of the baking plates and produces a deposit of comparatively uniform diameter in a manner which will be well understood. Immediately upon the delivery of this portion of the batter, the latch 33 drops into locking relation to the transverse bar 28 and the rearward movement of the pistons is commenced under the control of the mechanism yet to be described.

The reciprocation of the yoke 24 and the consequent operation of the pistons, is effected by the provision of a rocking shaft 37^A carrying arms 38 and 39 desirably respectively disposed at opposite ends of such shaft and preferably having removable anti-friction elements 40 and 41 carried in sockets in their ends and maintained therein by set screws 42 and 43. These anti-friction members are further designed to be longitudinally adjustable so as to lengthen or shorten the length of each arm and to thereby regulate the length of the period of effectiveness of each arm, in a manner to be hereinafter described. It will be understood that the arm 38 is intended to coöperate with the lower chain element and the arm 39 with the upper chain element and together, these arms in their coactive relation to these chain elements, serve to reciprocate the yoke 24. This reciprocating action is directly effected by the centrally depending arm 34, which is straddled by and pivotally secured as aforesaid, to the latch element 33.

The operation of this last described structure is as follows: Assuming that the device is in the position shown in Fig. 2, it will be understood that the arm 39 is under pressure from the chain element 6 preferably through the medium of one of the rollers or pins 8. Continued pressure upon this arm, causes the arm 38 to swing rearwardly and the dog 37 to ride upon the cam surface 18 and thereby lift the latch 33 to free the transverse bar 28 from the latch hook 35. Still further pressure then serves to draw the piston 29 toward the left, while the piston 22 is maintained stationary as aforesaid by the contact of the transverse bar 27 with the right-hand end of the cylinder. This motion continues until the desired quantity of batter is drawn into the cylinder, at which time the anti-friction element 41 of the arm 39 escapes from control of the upper chain element. Then, the arm 38 is struck by one of the pins 7 of the lower chain element, which contacts with its anti-friction member 40 and causes forward movement of the latch element. This forward movement of the latch element drives the yoke 24 forwardly and during this forward movement of the yoke, the pistons are in relatively unchanged positions. At about or just previous to the time the transverse bar 28 strikes the left-hand end of the cylinder, the dog 36 comes into contact with the surface 19 and raises the latch element 33. Continued forward movement of the arm 34 which is necessarily produced by the forward movement of the arm 38 and the consequent rocking of the shaft 37, causes the latch element 33 to completely free itself and results in the continued movement toward the right of the piston 29 in a manner to compress the batter which has been retained between the pistons. This compression of the batter continues until the pistons practically contact with each other and necessarily results in the positive discharge of the said selected portion of the batter from the delivery port 15 at which time the anti-friction element 40 escapes from control of the lower chain element 5.

It will be understood that the provision of the adjustable anti-friction element permits of a variable timing of the operation of the machine and that the effect of the pistons 22 and 29 may be somewhat varied by further adjustment which is provided for in the manner described.

What I claim is:

1. A batter pump for baking machines comprising a cylinder having inlet and outlet ports, opposing pistons, means for positively controlling each of said pistons when spaced on either side of said inlet port to relatively move them away from each other to charge said cylinder, and means for positively controlling each of said pistons when spaced on either side of said outlet port to

relatively move them toward each other to effect a discharge.

2. A batter pump for baking machines comprising a cylinder having inlet and outlet ports, opposing pistons, means for pocketing a quantity of batter between said pistons through said inlet, means for transferring said pocketed batter to a position over said outlet, and means for effecting a discharge of said batter by a movement of one piston toward the other. 70

3. A batter pump for baking machines comprising a cylinder having inlet and outlet ports, opposing pistons, means for pocketing a quantity of batter between said pistons through said inlet, means for transferring said pocketed batter to a position over said outlet, and means for positively controlling each of said pistons and moving them relatively to decrease the size of said 80 pocket when over said outlet port to expel said batter. 85

4. A batter pump for baking machines, comprising a cylinder having inlet and outlet ports, opposing pistons, means for pocketing a quantity of batter between said pistons through said inlet, means for transferring said pocketed batter to a position over said outlet and maintaining said pistons in relatively unchanged positions, and 90 means for positively arresting one of said pistons and moving the other after said transfer to expel the batter. 95

5. A batter pump for baking machines comprising a cylinder having inlet and outlet ports, opposing pistons, means for moving said pistons apart to form a pocket between them, means for simultaneously moving both pistons to transfer the batter drawn in to a position opposite the outlet, and means for positively arresting one of said pistons while further movement of the other causes the discharge of the batter. 100

6. A batter pump for baking machines comprising a cylinder having spaced inlet and outlet ports, opposing pistons, means for moving said pistons apart while at the inlet to pocket a charge of batter, means for transferring said pistons while in spaced 110 relation to the outlet, and means for moving said pistons into substantially abutting relation when over said outlet to effect a discharge of said batter. 115

7. A batter pump for baking machines comprising a cylinder having spaced inlet and outlet ports, opposing pistons, means for moving said pistons to cause a suction of the batter therebetween while the outlet port is closed, means for opening said outlet port, means for again moving said pistons to eject the batter contained in said cylinder at predetermined intervals while over said outlet port in their abutting relation, and means for returning said pistons 120 in their abutting relation to initial position. 125

8. A batter pump for baking machines comprising a cylinder having spaced inlet and outlet ports, opposing pistons, means for pocketing a charge of batter between 5 said pistons, means for closing said outlet port during the admission of said batter, means for moving said pistons into substantially abutting relation when said outlet has been opened to eject said batter, and means 10 for closing said inlet port while ejecting said batter.

9. A batter pump for baking machines comprising a cylinder having inlet and outlet ports, opposing pistons, means for pocketing a charge of batter between said pistons, one of said pistons closing the outlet port during the charging operation, means 15 for moving said pistons in spaced relation to the outlet, means for ejecting said batter, 20 the opposing piston closing the inlet port during the ejecting operation.

10. A batter pump for baking machines comprising a cylinder having inlet and outlet ports, opposing pistons, means for separating 25 said pistons at the inlet, means for moving said pistons in spaced relation to said outlet, means for arresting the movement of one of said pistons continuing the 30 movement of the other piston to close the space above said outlet.

11. A batter pump for baking machines comprising a cylinder having an inlet and an outlet, opposed pistons, means for simultaneously moving said pistons between the 35 inlet and outlet of said cylinder, and an automatically releasable locking device for maintaining said pistons in relatively unchanging positions during such movement.

12. A batter pump comprising a cylinder 40 having an inlet and an outlet formed therein, opposed pistons operating within said cylinder, automatically releasable means for maintaining said pistons in spaced relation and means for simultaneously moving them 45 from the inlet to the outlet of said cylinder, and for moving said pistons relatively toward each other to expel the batter taken in through the inlet upon the release of said automatically releasable means.

13. A batter pump comprising a cylinder 50 having an inlet and an outlet, opposing pistons, means for moving said pistons apart while at the inlet in said cylinder to draw in the batter, means for transferring said pistons, automatically releasable means for locking said pistons in spaced relation to said outlet, and means for moving said pistons together while at said outlet upon release of said locking means.

14. A batter pump for baking machines comprising a cylinder having an inlet and an outlet, said inlet being connected to a source of batter supply, opposing pistons,

means for moving said pistons between the inlet and outlet of said cylinder, automatically releasable means for locking said pistons together during such movement and means for automatically moving said pistons relatively upon release of said locking means.

15. A batter pump for baking machines comprising a cylinder having an outlet and an inlet connected to the source of batter supply, opposing pistons, means for moving said pistons between the inlet and outlet of said cylinder, automatically releasable means for locking said pistons together, means for automatically releasing and moving said pistons apart while adjacent the inlet of said cylinder to form an expanding chamber for drawing in the batter, and means for moving said pistons toward each other while the cavity therebetween is in communication with the outlet of said cylinder.

16. A batter pump for baking machines comprising a cylinder having an outlet, and an inlet connected to the source of batter supply, opposing pistons, means for moving said pistons between the inlet and outlet of said cylinder, automatically releasable means for locking said pistons together, means for releasing and moving said pistons apart while adjacent the inlet of said cylinder to form an expanding chamber for drawing in the batter, and means for automatically releasing and moving said pistons toward each other while the cavity therebetween is in communication with the outlet of said cylinder.

17. A batter pump for baking machines comprising a cylinder having an outlet, and an inlet connected to a source of batter supply, opposing pistons, means for moving said pistons between the inlet and outlet of said cylinder, automatically releasable means for maintaining said pistons relatively immovable for a period of their travel, and means for governing such period of travel by control of said last-named means.

18. A batter pump for baking machines comprising a cylinder having an outlet, and an inlet connected to a source of batter supply, opposing pistons, means for moving said pistons between the inlet and outlet of said cylinder, an element for connecting said pistons, a latch element for controlling the position of said element, and means for automatically moving said latch element into varying positions.

In testimony whereof I affix my signature in presence of two witnesses.
